(57) **CLAIM**

I claim the ornamental design for a combined pet book toy and feeding dish, as shown and described.

DESCRIPTION

FIG. 1 is a top, left, front perspective view of a combined pet book toy and feeding dish showing my new design with the cover in an opened position;

FIG. 2 is a top, right, rear perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a top, left, front perspective view thereof in an alternate, closed position.
